BALL THROWING DEVICE

Martin Goldman, Jackson Heights, N. Y.

Application November 21, 1950, Serial No. 196,774

15 Claims. (Cl. 124—21)

1

This invention relates to ball throwing or pitching machines designed to throw base balls, tennis balls or the like to an individual stationed at a predetermined distance from the machine, who endeavors to strike the thrown ball with a base ball bat, racket or other suitable ball hitting instrument.

Various novel objects are involved in this invention and are enumerated as follows:

1. The machine is to be provided with means attachable to the machine, for rolling the machine from one location to another and detachable from the machine when it is desired to set the machine immovable in location.

2. The inclusion, in a ball throwing machine of the character described, of a magazine for holding a multiplicity of balls and discharging the ball from the magazine, one at a time and in consecutive order, upon guides which deposit the ball upon an impeller mechanism which will project the ball from the machine.

3. Including means for regulating the discharge intervals between a predetermined number of balls from the magazine and automatically stopping the operation of the machine when the last of the predetermined number of balls has been discharged from the magazine and projected from the machine.

4. The inclusion of automatically operated signaling means to indicate that a ball is about to be projected.

5. The inclusion of a remote switch controlling means located at a point distant from the machine but convenient to the batter whereby the operation of the ball throwing machine may be controlled at that point.

6. The inclusion of means for changing the angle or vertical direction of the path of the projected ball.

7. The inclusion of means for horizontally shifting the projecting mechanism of the machine to control the direction horizontally of the path of the projected ball.

8. The inclusion of stretchable, endless impeller elements which are rotatably mounted upon the machine and rotate about their supports to reduce the wear and tear of the stretchable, endless impeller elements.

9. The inclusion of a flexible strap disposed between and connected to the stretchable endless impeller elements and cushioned bumper elements to receive and soften the impact of the flexible strap.

10. The inclusion of means for centering the ball, which is to be discharged from the magazine, upon an impeller mechanism forming a part of this invention.

11. The inclusion of disengageable linking means by the use of which the stretchable end-

2

less impeller elements may be easily and quickly removed for replacement.

12. The inclusion of a removable split covering member suspended over the impeller mechanism and having an orifice at its front end aligned with the path of a ball as it leaves the machine.

13. The inclusion of filler rings or spacer washers upon impeller supporting bolts to adapt the supporting bolts to the width of the stretchable endless impeller elements.

14. A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will best be understood from the following description of a specific embodiment when read in connection with the accompanying drawing, in which:

Fig. 1 is a side elevational view, showing a cover member in section and with other parts broken away.

Fig. 2 is a view, in elevation, of the opposite side of the machine and shows the cover member in section and parts of the supporting frame or stand broken away.

Fig. 3 is an elevational view of the front or ball discharging end of the machine and shows portions broken away and omitted.

Fig. 4 is a fragmentary detail, in elevation, of a part of the machine and will hereinafter be fully described.

Fig. 5 is also a fragmentary, elevational view of a part which will be hereinafter described.

Fig. 6 is a rear view in elevation, of the machine and shows portions broken away.

Fig. 7 is an enlarged detail view of a part which will be hereinafter described.

Fig. 8 is a sectional view of same taken along the line 8—8 of Fig. 7.

Fig. 9 is a fragmentary detail in elevation, taken along line 9—9 of Fig. 7.

Fig. 10 is a plan or top view of the machine having the ball magazine removed and part of the top of the covering member broken away to disclose the impeller mechanism of the machine.

Fig. 11 is a partial top view, having the cover-

ing member removed and looking into the open top of the ball magazine which is shown without balls and with parts broken away.

Fig. 12 is a plan view, in enlarged scale, of a portion of an impeller unit which forms a part of the ball throwing machine and shows parts broken away.

Fig. 13 is a side elevational view of same and shows parts broken away.

Fig. 14 is a plan view of a detachable link member which forms a part of the impeller unit and will hereinafter be described, and

Fig. 15 is a sectional elevation taken along line 14—14 of Fig. 11.

Referring in detail to the parts, 11 designates a main supporting stand or frame having legs 12 converging at the top and welded or otherwise secured to a cross-bar 13 and diverging toward their lower ends (Fig. 3) and welded or otherwise secured to a cross-bar 14 near the lower end of legs 12. The lower ends of the legs 12 are provided with wheels 15 (Figs. 2 and 3). The rear end of the supporting frame is provided with legs 16 also converging at their top ends which are welded or otherwise secured to a cross bar 17 and diverge downwardly to their lower ends which are without wheels and rest firmly upon the ground. Slidably mounted upon the cross-bar 13 is a pair of spaced cheek members 18, having disposed between and welded or otherwise secured to them, a channel member 19, forming thereby an integral unit embracing the cheek members 18 and the channel member 19.

A block 20 (Figs. 7 and 8) is pivotally mounted upon the cross-bar 13 and is held approximately centrally between the cheeks 18 by means of a pin or dowel 21 secured upon the cross-bar 13 by a bolt 22 of which it forms a part. The block 21 has a bore 23 within which the pin 21 engages and this bore is slightly elongated along the longitudinal axis of the machine to allow for a slight longitudinal movement of the block with respect to the position of the pin or dowel. The block 20 is further provided with a horizontal internally threaded bore 24 through which a threaded portion 25 of a turntable rod 26 engages. The said rod 26 extends through bushings 27 which are attached to the rod 26 and are formed with narrowed shanks 28 which engage through orifices in the cheeks 18. The rod 26 may be extended at either side and terminates in a handle 29 by means of which the rod 26 may be rotated clockwise or counterclockwise to move the cheeks and channel to the right or left as may be desired, to change the horizontal direction of the flight of the ball as will be further explained. Referring now to Figs. 7, 8 and 9 it will be noted that the sliding member consisting of the cheeks 18, channel 19 and partially threaded turntable shaft 26 may be laterally movable upon the cross-bar 13 and may be held thereon against accidental displacement by means of depending tongues 30 and are held therein by washers 31 and bolts 32 which are threaded into the depending tongues 30. This slotted connection, however, may be omitted if desired, and the cheeks and connected parts held thereon by gravity exerted by the weight of the mounted impeller mechanism as will be hereinafter described.

The cross-bar 17, heretofore mentioned, has welded or otherwise secured to it, a boss 33 (Figs. 1, 2 and 6) and a short distance below the boss is a cross-bar 34 which is secured between the rear legs 16. Both the boss 33 and the cross-bar 34 have aligned threaded bores 35 and 36 respec-

tively through which a threaded bar 37 engages. Upon the lower end of the threaded bar 37 there is provided a handle 38 by which the threaded bar 37 may be turned. The upper end of the threaded bar 37 is rounded as at 39 and engages in a rounded or concave pocket 40 formed upon a plate 41 to which the rear ends of elongated angular members 42 and 43 are welded or otherwise secured. The said elongated angular members 42 and 43 form the base members of a secondary supporting frame which carries the operating and ball projecting mechanism of the machine. The front or forward ends of the angular members 42 and 43 are pivotally attached to the cheeks 18, heretofore mentioned (Figs. 1, 2, 3, 6, 7 and 8) by means of a bolt 44 and spacer tube 45. The pivotal connection just described, coacting with the threaded bar 37 at the rear end, provides a means for vertically tilting the angular members 42 and 43 which members carry the impeller mechanism of the ball throwing machine as now to be described.

Secured to the top and near the rear end of the angular members 42 and 43 (Figs. 1, 2 and 6) there is a channeled cross-piece 46 which has a cut out portion 47 (Fig. 6) and has reinforcing webs 48 which are welded to the top of the angular members 42 and 43 and to the channeled cross piece 46. A bar 49 secured to the top of the channeled cross-piece 46 extends outwardly from one side and a second bar 50 also secured to the top of the channeled cross-piece 46 extends outwardly in the opposite direction. To the outer ends of the outwardly extending bars 49 and 50 there is secured upstanding supporting rods 51 and 52 respectively to which the ends of horizontal diverging carrier bars 53 and 54 respectively are attached. The diverging carrier bars 53 and 54 are further supported, approximately at their centers, by means of upstanding rods 55 and 56 respectively which rods are in turn carried and secured to a cross-plate 57 (Fig. 10). The cross-plate 57 rests upon and is secured to the flange of the angular members 42 and 43 (Figs. 1, 2 and 10). Attached to the outer ends of the carrier bars 53 and 54, as at 58 and 59, is a partially circular band 60, shown in Fig. 10, by dot-dash lines. The said circular band and part of its connected carrier bars form a support for an enclosing or covering member 61 which is formed with downwardly projecting side walls 62 along the front and sides and partly across the rear. The said covering member is made up of two sections and has joining edges along a central line (not shown) extending from a point P to the front wall and down the front wall along the line L, as shown in Fig. 5, which also shows an opening 63 through which the balls emerge from the machine after leaving an impeller unit which will presently be described. A circular opening 64 in the top of the covering member 62 is provided wherein a magazine 65 is adapted to set and rest upon the carrier bars 53 and 54. Suitable means (not shown) may be provided for securing the magazine to the carrier bars.

A pair of bearing blocks 66 are suitably secured to the flanges of the elongated angular members 42 and 43 near their forward ends, and carry a shaft or axle 67 upon which is mounted an idle sprocket wheel 68 while near their rear ends there is secured, in any suitable manner, upon the flanges of the angular members 42 and 43 a second pair of bearing blocks 69 through which a drive shaft 70 engages. A drive sprocket wheel

71 is secured to the shaft 70 and has a drive gear 72 (Fig. 1) also secured to the shaft 70. A worm gear 73 engages the drive gear and forms the upper portion of an upright shaft 74 which is suitably mounted in a bearing 75 on a cross-bar 76. The shaft 74 extends downwardly and carries, at its lower end, a pulley 77 and a drive belt 78 which connects the pulley 77 with a motor driving pulley 79 upon the shaft 80 of a motor 81. The motor 81 is suitably mounted upon a plate 82 which is in turn mounted upon and swings about a depending rod 83, which rod is securely welded or otherwise attached to the angular member 42. To hold the belt 78 in tight contact with the pulley 77 and the motor driving pulley 79 there is provided a tension spring 84 which is disposed between the swinging motor carrying plate 82 as at 85 and the leg 12 at 86. Engaging over the sprockets 68 and 71 is a chain belt 87 having pins 88 and 89 which extend laterally upon both sides of the chain belt 87 and are spaced equally distant upon the chain belt. The said belt, when driven by the worm and gear connection with the motor drive, travels in the direction indicated by the arrow shown in Figs. 1 and 2.

A cross-bar 90, T-shaped in cross section, is notched into and welded to the bearing blocks 66 at the front end of the machine, as at 91 (Figs. 1, 2 and 10) and carries upon each end a plate 92 and 93 having narrowed extensions 94 and 95 respectively. To the said extensions 94 and 95 there is attached upright pins or bolts 96 and 97 (Figs. 1, 2, 3 and 10) which are held upon the plate by threaded ends 98 (Fig. 13) which engage through threaded bores in the said extensions 94 and 95, and are secured by nuts 99. The said pins or bolts 96 and 97 carry the impeller unit which will now be described.

Engaging over each of the upright bolts 96 and 97 is an endless stretchable belt 100 and 101 (Figs. 3, 10, 12 and 13). The stretchable endless belts 100 and 101 also engage pins or bolts 102 and 103 which are connected by links 104 and 105 to pins or bolts 106 and 107, in turn embraced by split clamps 108 and 109. A strap 110, of leather or other suitable non-stretchable, flexible material, is secured between the split ends of the clamps 108 and 109, thus connecting the stretchable endless belts into a single impeller member as best shown in Figs. 3, 10, 12 and 13. Referring to Figs. 12 to 15 inclusive, a means is shown whereby an intermittent motion in the direction indicated by the arrows X in Fig. 12 is imparted to the stretchable endless belt 101. As will be presently fully explained, the strap 110 is drawn back and stretches the endless belts 100 and 101 to a predetermined point when it is automatically released under great pressure and resumes its normal state striking against bumpers, the relative position of which is shown by the dotted circular lines in Fig. 12, and creating a force which gives a partial rotative movement to the endless belt equal to about one-thirtieth of its length, in the direction indicated. Thus this movement of the endless belt equally distributes the wear and tear upon the belt and greatly prolongs the useful life of the same. To facilitate this movement there is provided a collar or tube 111 which engages loosely around the bolt 97, a second tube 112 encircles the tube 111 but is spaced apart from it and disposed between the two tubes and needle roller bearings 113. A similar arrangement of tubes and needle bearing is employed on the bolt 103. The width of the

endless belt may vary within certain limits and to meet any variation in the width of the belt beyond that shown in Fig. 13, filler rings or washers 114 may be removed as desired. The bolt 103 is formed with a cap 115 over which the upper, and if desired the lower link 105 may engage. For this purpose an elongated opening 116 is formed in the links. One part 117 of the elongated opening has a diameter slightly larger than the diameter of the cap 115 allowing the cap to pass therethrough, while a portion 118 is of a smaller diameter to engage the stem 119 of the bolt 103. With such an arrangement the endless belt is easily removed for replacement purposes by slightly turning the nut 120 upon the bolt 107 to give play to the link. While this description of belt mounting and link connections has been confined to one of the two endless belts upon the machine, it is nevertheless obvious that the same construction is applied to the endless stretchable belt 100 forming the other end of the impeller unit. The bumpers referred to are best shown in assembly, in Fig. 3, where they carry the reference numerals 121 and 122 and are secured upon flat bands forming tracks 123 and 124 respectively. The tracks extend almost along the entire length of the apparatus as best shown in Figs. 1, 2 and 10.

The tracks 123 and 124 are secured at their forward ends, upon blocks 125 and 126 respectively, the said blocks being in turn secured upon the T-shaped cross-bar 90. At approximately their central point the tracks are supported by upstanding members 127 and 128 spaced apart and secured to the flanges of the angular members 42 and 43 upon either side of the chain belt 67 and allowing clearance for moving parts between them. At the rear the tracks are supported upon the outwardly extending bars 49 and 50. In roller engagement upon the tracks 123 and 124 there is a base plate 129 adapted to reciprocal rolling movement, rollers 130 being provided near the four corners of the base plate for this purpose. Upon the rolling base plate 130 there is secured an upstanding slotted block 131 within the slot of which there is pivotally mounted at 132 a lever 133 having a long and short arm. The short forwardly extending arm terminates in a hooked coupler element 134 while the rearwardly extending, long arm is provided with a laterally extending pin or finger 135 (Figs. 1, 2, 6 and 10) which engages with an adjustable cam element 136 when the base plate carries the pin or finger 135 to the point of contact with the cam element 136, as will be explained. A second upstanding block 137 is also mounted upon the rolling base plate 129 and has pivoted thereto (Fig. 2) a bent lever 138, pivoted to the block 137 at 139. The lever 138 is formed with a rearwardly and upwardly extending arm 140 which acts as a pawl member and engages with a ratchet wheel 141 directly under the floor of the ball magazine 65, which rotates the ball feeding mechanism, as will be hereinafter described. A rearwardly extending portion 142 is weighted to overcome the weight of the pawl member 140 and which moves about its pivotal connection 139. A third upright block 143 is secured to the forward end of the rolling base plate 129 and is formed with a central orifice or passage 144 (Fig. 2) through which a hooked coupler member 145, which is secured upon the aforementioned strap 110, engages and will be hereafter fully explained. The hooked coupler member 145 is adapted to

engage the hooked coupler member 134 as clearly shown in Fig. 1.

The description now goes back to the impeller unit which will now be described in more detail, reference being had to Figs. 3, 10, 12, 13 and 15. As already set forth, the impeller unit as a whole comprises the stretchable endless belts 109 and 104 (the stretchable belt 109 not being shown in Figs. 12 and 13), each mounted upon standards or bolts 96 and 97 respectively and having link connections with a flexible strap member 110. Included also in the impeller unit is an impeller element attached to the strap 110 and comprising a rear plate 146 and a front plate 147 which are riveted together, through the strap 110, by rivets 148 formed with heads 149 and having extending semi-spherical buttons or knobs 150 that act as a centering means and hold a projected ball in proper alignment for the throw. The heretofore mentioned hooked coupler 145 is attached to the plates 146 and 147 and has a narrowed shank 151 which extends through rear plate 146, strap 110 and front plate 147 and is riveted as at 152. The bumpers consist of bolts 153 and 154 which are secured, in upright position, to the tracks 123 and 124 respectively and each is covered with a thick layer of any suitable resilient material 155 and 156 respectively.

The plates 92 and 93 carrying the bolts 96 and 97 are slidable upon the upper flange of the T-shaped cross-bar 91 and may be adjusted by means of threaded shafts 157 and 158 respectively, which shafts are turnably attached at 159 and 160 to projecting lugs 171 and 162 upon the T-bar 91, engage through threaded bores in lugs 163 and 164 depending from the plates 92 and 93, and are provided with crank handles 165 and 166. Yoke members 167 and 168 are attached to and depend from the plates 92 and 93 and are slidable against either side of the T cross-bar 91. Set screws 169 and 170 engage through the yoke members 167 and 168 and provide a means for securely tightening the plates in position. Upon releasing the hold of the set screws 169 and 170 upon the attached plates 92 and 93, the said plate may be moved in either direction along the T cross-bar to shift the impeller unit and properly align the impeller carrying the centering buttons or knobs 150. Depending lugs 92' and 93' are secured to the under side of the plates 92 and 93 respectively and engage along the outer edges of the flanges of the T bar 90 and act as guides for the plates 92 and 93 and slide along same.

Secured to the aforementioned rolling plate 129 and extending downwardly between the tracks 123 and 124 are fingers 171 and 172 with which the laterally extending pins 88 or 89 upon the chain belt 87 engage. The said laterally extending pins upon both sides of the moving chain belt 87 contacting the fingers will move the rolling base plate 129 and its attached parts rearwardly until the pins 88 upon the chain belt becomes disengaged with the said pins. The rolling base plate being released from contact with the moving chain belt is brought forward by means of a cable 173 attached at one end to a cross-bar connecting the fingers on both sides of and spanning the chain belt as at 174. The said cable 173 passes over a pulley 175 mounted in standards 176 which are secured upon a cross plate 177 which is in turn secured to the flanges of the angular members 42 and 43. From the pulley 175, the cable 173 passes over a guide

roller 178, rotatably mounted in a cylindrical weight housing member 179, then down the cylindrical weight housing member 179 to a weight 180 to which its end is attached as at 181. The said weight being sufficient heavy to draw the said rolling base-plate 129 in a forwardly direction when same is free from finger contact with the chain belt 87. The cam element 136 is slideable upon the track 124 and is adjustable, in a longitudinal direction by means of a threaded shaft 182, the inner end of which is rotatably mounted in a bearing block 183 which is stationary upon the track 124. From the bearing block 183 the threaded shaft 182 passes through a threaded bore in the cam element 136 and has its outer end rotatably mounted in a second bearing block 184 which is also fixed upon the track 124. A crank handle 185 is provided for turning the shaft to slide the cam 136 to the desired position. The pin 186 upon the lever 133 hereinbefore mentioned will strike the beveled front edge of the cam, ride up the beveled edge and continue along the extending arm 186 until the fingers 171 and 172 are disengaged from the chain belt 87. A supporting track member 187, supported upon the cross-bar 57 and a second cross bar 188, may be provided along which the chain belt may move. The cylindrical weight housing member 179 is attached to a plate 189 which is securely attached between the cheeks 18 and above the channeled cross member 19 and is formed with a forwardly extending arm 190 which contacts and is welded or otherwise secured to the cylindrical weight housing member 179.

Pivottally attached at 191 to the cylindrical weight housing member 179 and mounted between cheek pieces 192 welded or otherwise secured to cylindrical housing member, is a semaphore type signal element 193. See Figs. 2, 3, 4 and 10. The inner edge of the semaphore is formed with a triangular shaped cam 194 which projects into the cylindrical weight housing 179, through a slot 195. The upper end of the semaphore 193 terminates in a disk 196 which moves into the position shown in Fig. 4, due to the urge of a spring 197 attached at one end to the semaphore at 198 and attached at its opposite end to an orificed lug 199 upon the arm 190, when the weight 180 is positioned below the cam projection. When the weight 180 rises to the position shown in Fig. 3, it forces the semaphore outwardly as shown. In Fig. 5 the semaphore disk 196 is shown as it appears in line with the opening 63 in the front wall 62 of the covering member 61 indicating to the batter that no ball is ready to be projected from the machine. A broad colored ring 200, preferably red, may be applied around the opening 63 to emphasize the outline of the opening.

The ball discharging mechanism is best illustrated in Figs. 1 and 11 and comprises the magazine 65 having a fixed bottom 201 formed with a ball discharging opening 202. The ratchet wheel 141 is attached to a shaft 203 which extends upwardly into the ball magazine 65 and has secured to it a drum comprising a lower plate member 204, a top member 205 and an annular wall 206. The said drum is securely attached to the shaft 203, by welding or otherwise, and turns with the shaft when same is rotated. Separator or spacer rings 207 and 208 are welded to the base plate 204 and rotate with same. It will be noted (Figs. 1 and 11) that the diameter of the drum is considerably less than the diam-

eter of the ball magazine and that the annular wall 206 of the drum and the lower portion of the wall of the magazine 65 form a trough 206' in which a series or multiplicity of tubular members or ball pockets 207 move. The said pockets are welded or otherwise securely attached to the annular wall 206 of the said drum. An inverted pan shaped member comprises a top 208, which slips freely over the shaft 203 and an annular side wall 209 which rests freely upon the top member 205 of the drum. Balls 210 are held within the magazine 65 and are adapted to drop from the top 208 over its side into the pockets 207. A ball 210 indicated by dot-dash lines in Fig. 1, when discharged through the opening 202, will drop upon an upper runway comprising tracks 212. The said runway 212 is mounted upon the said rolling plate 129 and holds the ball in the position shown by the dot-dash lines until the forward ends 213 of the runway have passed rearwardly beyond the ball discharging opening 202 when the said ball will drop to a second runway 214 which is also secured to and extends forwardly to a point beyond the ends 213 of the runway 212. To keep the ball temporarily in the position shown in Fig. 1, there may be provided depending stop members 215 and 216 (Figs. 1 and 11). A stop or holding member 217 is attached to the wall of the magazine and is positioned above the opening 202 (Figs. 1 and 11) in the bottom 201 and is employed to prevent any ball from the magazine from dropping into the pocket over the opening 202 as will be further explained. The consecutive operation of all the parts heretofore described will be herein-after more fully described and explained.

A switch and connection box 218 containing a conventional solenoid operated switch and connections and has connected to it a flexible conductor cable 219 which supplies power from its source. A conductor 220 leads current from the connection box to the motor 81. A conductor cable 221 leads from the connection box 218 to a remote control switch 222 which may be located at a distance from the machine. Still another flexible cable conductor 223 leads from the connection box 218 to a second connection box 224 upon the wall of the magazine 65. The connection box 224 may be supplied with an electrically controlled counting means which is actuated by means of a microswitch (not shown) located within the connection box 224 and has its actuating pin 225 projecting through the wall of the magazine 65 in alignment with tripping lugs 226 upon each of the ball pocket members 207. An additional tripping lug 227 is provided upon one of the ball pocket members, which is aligned with the actuating pin 225 of a second microswitch (not shown) in the connection box 224. The said micro-switch, actuated by the pin 225, controls the current to a solenoid switch, located in the connection box 218, through which current is fed to the motor 81. A conductor 229 leads from the connection box 224 to a lamp socket 230 upon the front wall of the magazine 65.

To facilitate the movement of the machine from place to place, there is provided a long bent lever 231 having a cross-handle 232 at its upper end and a roller or wheel 233 mounted in a hub 234. From the hub there projects, approximately at right angles to the lever 231, a short arm 235 having a hooked end 236 which may be passed under a cross-bar 237 secured between the rear legs 16. The hooked end 236 is adapted to engage in an orifice 238 and when the handle 232

and the lever 231 is pulled downwardly, the hooked end 236 will enter the orifice as far as a shoulder 239 at the base of the hooked neck, and lift the legs 16 and allow the machine to be rolled.

5 The various switches and the connections thereto are all standard and conventional and it is therefore deemed unnecessary to go into any detailed description regarding same.

Operation

10 The position of the parts, at the start of the machine, are as shown in Fig. 1 where the impeller unit and the impeller retracting or stretching mechanism are locked together. The rolling base plate 129 with its attached parts is shown in its forward position and is held thus by means of the weight 189, connected by cable 173 to the fingers 171 and 172 depending from the rolling base plate. In the said position the hooked coupler 134 which is pivotally mounted upon the rolling base plate, is in engagement with the hooked coupler 145 which is in turn secured to the plates 146 and 147 upon the impeller strap 110. The drum rotating pawl 138 which is pivotally mounted upon the rolling base plate 129 is shown in engagement with the drum rotating ratchet wheel 141. It might here be noted that as the balls 210 are loaded into the magazine 65 the first balls will roll off the top 139 of the inverted cam shape member and fall into all of the pockets 207 with the exception of the pocket directly over the ball discharge opening 202 in the fixed bottom 201 of the magazine 65. The stop 217 blocks any ball from dropping in the pocket over the opening mentioned. The semaphore signal disk 196 is in place over the opening 63 in the front wall of the covering member 61.

20 A starting button upon the connection box 218 or at the remote control switch box 222 may now be pressed to throw a starting switch to send current to the motor 81 and light the lamp in the socket 230. The lighted lamp in the socket indicates that the machine is in operation. With the motor running a drive through the motor pulley 79, belt 78, large pulley 77 and shaft 74 upon the upper end of which there is a worm 73, is created to rotate the worm. A gear wheel 72 upon a shaft 70 engages the worm 73 and rotates a sprocket wheel 71 also secured upon the shaft 70. The sprocket 71 gives motion to a chain belt 87 and an idler sprocket 68 supports the opposite end of the chain belt, which obviously is an endless belt. The pins 88 extending from each side of the chain belt are about to engage the fingers 171 and 172 which are attached to and depend from the rolling base plate 129.

25 The continued movement of the chain belt 87 brings the pins 88 into contact with the fingers 171 and 172 and begins the rearward movement of the rolling base plate 129 drawing with it, by means of the connected hooked couplers 134 and 145, the impeller and its connected strap 110, and stretching the attached stretchable endless belts 100 and 101.

30 The rearward movement of the rolling plate continues to approximately the position shown in Fig. 2 and by the dot-dash lines in Fig. 10, when the pin 135, projecting laterally from the lever 133, begins to ride the beveled edge of the cam 136. During this movement of the chain belt 87 and just prior to its reaching the point described, the pawl lever 138, pivotally mounted upon the rolling base plate 129, and in engagement with the ratchet wheel 141, rotates the drum in the magazine 65 and brings a ball in the first ball

11

pocket 207 into line with the ball discharging opening 202 where it drops through to the runway 212 (Fig. 3 and dot-dash line in Fig. 1). The ball remains in this position until the ends 213 of the runway have passed the discharge opening, at which point the ball drops off same and lands upon the second or lower runway 214 in front of the impeller plate 147. The rolling base plate 129 is at this point, still moving rearwardly and continues to do so to bring the pin 135 into contact with the cam 136 and cause said pin to ride up the beveled edge of the cam 136 and move the hooked coupler 134 out of engagement with the hooked coupler 145 which is attached to the impeller plates 146 and 147 and to the strap 110. The disengagement of the two said hooked couplers releases the impeller whereupon the tension created in the stretchable endless belts 100 and 101 causes the same to snap forward, impelling the ball along the runway 214 and project the ball, with speed and force, outwardly from the machine, through the opening 63 in the wall 62 of the covering member 61.

After the disengagement of the hooked couplers 134 and 145, the rolling base plate 129 continues its rearward movement until the downward movement of the pins 88 on the chain belt, as they pass around the idler sprocket 68, releases the fingers 171 and 172. The rearward movement of the fingers 171 and 172 will draw the weight 180, within the cylindrical housing 179, upwardly and force outwardly, as it passes, the cam 194 upon the semaphore 193 (Fig. 3) thus allowing free passage through the opening 63 of the ball as it is ejected from the machine. When the weight 180 drops below its contact with the semaphore cam 194, the disk 196 upon the semaphore 193 resumes the closed position shown in Figs. 4 and 5.

The point at which the hooked couplers 134 and 145 are released may be varied by adjusting, longitudinally, the cam 133 which, as stated, is slidable upon the track 124 and movable thereon by means of the threaded shaft 132 which may be rotated by the handle 135. The vertical and horizontal adjustments of the machine by means of the threaded vertical shaft 31 and handle 33 at the rear portion of the machine and the threaded horizontal shaft 26 and handle 29, has already been described and needs no further description.

The apparatus illustrated in the drawings is particularly designed to project fifteen balls, in consecutive order, from the machine. After the fifteenth ball has been impelled and projected the current to the machine is automatically cut off and the operation of the machine stops. This automatic cut off is accomplished by the means now to be described. A microswitch in the connection box 224 has its actuating pin 223 projecting through the wall of the magazine, into the trough 206'. A lug 240, upon the outer wall of one of the pockets 207' is adapted to engage and trip the actuating pin 223 of the microswitch which energizes a solenoid switch in the connection box 228 which, in turn, will actuate a solenoid switch in the connection box 218 and break the circuit to the motor 81 and lamp socket 230. The counting device is actuated by a second actuating pin 225 of a second micro-switch in the connection box 224. This second actuating pin is depressed by lugs 226 formed upon each of the pockets 207 (Fig. 11). The bumpers 153 and 154, as already described, will soften the im-

12

pact of the impeller when the strap portion 110 thereof strikes same.

I claim:

1. A ball pitching machine comprising a main supporting frame having front legs, wheels upon the front legs, rear legs the lower end of which rest upon the ground, a secondary supporting frame adjustably attached to the main frame, a ball magazine supported upon the secondary frame, a ball discharging opening in the bottom of the magazine, a rolling base plate reciprocally movable upon tracks on the secondary frame, a hook shaped coupler member pivoted upon the rolling base plate, fingers depending from and attached to the said rolling base plate, an endless chain belt upon sprockets rotating in bearings upon the secondary supporting frame, pins upon the endless chain belt engageable with fingers depending from the rolling base plate, a worm gear turnable with one of the sprockets, a worm engageable with the worm gear to rotate the sprocket and move the chain belt, a motor having a pulley and belt connection with the worm to drive the chain belt, a ratchet wheel upon the magazine and attached to a shaft extending upwardly into the magazine and rotatable therein, a drum in the magazine attached to the shaft and rotating with same, a multiplicity of tubular pockets attached to the drum and rotating with same, a pawl, pivotally mounted upon the reciprocally rolling base plate and engageable with the ratchet wheel upon the magazine, balls carried in the magazine and adapted to drop into the tubular pockets, each intermittent rotating movement of the drum bringing a ball into alignment with the ball discharging opening in the bottom of the magazine, an impeller unit upon the secondary supporting frame, the impeller unit comprising a pair of stretchable endless belts mounted upon the secondary supporting frame, a flexible strap disposed between and connected to the endless stretchable belts, impeller plates secured upon the flexible strap, a hook shaped coupler member upon the impeller plates and extending rearwardly to engage and lock with the hook shaped coupler member upon the rolling base plate and draw the impeller unit rearwardly to stretch the stretchable endless belts, a runway upon and moving with the rolling base plate to receive a ball when it drops through the ball discharging opening in the magazine, a second runway attached to the rolling base plate to which the ball drops from the first mentioned runway to the second runway after the impeller plates of the impeller unit have passed, in their rearward movement, the ball discharging opening in the magazine, the hooked coupler member upon the rolling base plate having a rearwardly extending lever arm, a pin attached to and extending laterally from the rear end of the extending lever arm, an adjustable cam upon the secondary frame engageable with the laterally extending pin to raise the lever arm and disengage the hooked end coupler members to release the impeller plates and project the ball from the machine, a weight vertically movable in a cylindrical housing attached to the secondary supporting frame adapted to draw the rolling base plate back to its starting point after the rolling base plate has completed its rearward movement, a conductor cable for supplying an electrical source to the motor of the ball throwing machine and switches for controlling the current supply.

2. A ball pitching machine as defined in claim 1, including the means therein for preventing more than one ball dropping through the ball discharge opening in the magazine, said means comprising a stop shelf inside the magazine and projecting over the ball discharging opening and above the ball pocket.

3. A ball pitching machine as defined in claim 1, including a lever having a wheel mounted upon its lower end and having a hooked end extending from the lower end at approximately right angles to the lever, the hooked end adapted to engage a cross bar between the rear legs of the main supporting frame, the said lever adapted when drawn downwardly to lift the rear legs and allow the main frame and machine thereon to be wheeled about.

4. A ball pitching machine as defined in claim 1, including means employed to maintain the ball upon the upper runway after it drops through the discharging opening, the said means comprising a front and rear stop member depending from the bottom of the magazine in line slightly beyond and slightly to the rear of the ball discharging opening in the magazine.

5. A ball pitching machine as defined in claim 1, including a means for cutting off the electric power and stopping the operation of the machine when a predetermined number of balls have been projected from the machine, the said means comprising a lug upon one of the said ball pockets engageable with a micro-switch actuating pin extending into the magazine and in the path of the lug upon the ball pocket, actuating the micro-switch to cut off the current and automatically resetting the starter switch.

6. A ball pitching machine as defined in claim 1, including a signaling means to indicate when a ball is about to be projected from the machine, the said means comprising a semaphore type signal arm pivotally attached to the weight housing cylinder, a cam on the semaphore arm extending through a slot into the said housing in the path of the enclosed weight and operated by the weight when it rises in the cylindrical housing.

7. The ball pitching machine as defined in claim 1, including a remote starting and stopping switch located at a distance from the machine and electrically connected to and operating a starting and stopping switch on the machine.

8. The ball pitching machine as defined in claim 1, including means for changing the vertical angle or direction of the path of the projected ball, the said means comprising a vertical, threaded rod mounted in bearings on the main frame and having a turning handle at its lower end, the upper end of the threaded rod having a rounded half spherical head engageable in pocket upon a block secured to the secondary frame and the said secondary frame having a pivotal connection at one end with the main frame.

9. The ball pitching machine as defined in claim 1, including means for changing the horizontal angle or direction of the path of the projected ball, the said means consisting of attaching the front end of the secondary supporting frame to upright cheek members slidable upon the main frame and having a threaded and handled shaft rotatable through and held upon the cheek members and the threaded portion of the shaft engaging through a threaded bore in a block pivotally fixed upon the main frame.

10. The ball pitching machine as defined in claim 1, in which the stretchable endless belts are mounted upon bolts which are secured to the secondary frame and to the link connection elements and have tubular members engaging around them, needle shaped roller bearings engageable against the tubular members and a second tubular member engageable over and around the needle shaped roller bearings upon which the stretchable endless belts are mounted.

11. The ball pitching machine as defined in claim 1, including cushioned bumper elements secured upon the secondary frame to receive and soften the impact of the stop portion of the impeller unit.

12. The ball pitching machine as defined in claim 1, including a means upon the impeller unit for centering the ball as it is projected from the machine, the said means comprising projecting buttons upon the impeller plate, each button being equidistant from the central point of the plate.

13. The ball pitching machine as defined in claim 1, wherein the connecting links are formed with enlarged openings connected with a smaller opening which encircles a bolt attached to the lower link and formed at their upper ends with a cap which is passable through the larger openings in the links, to expedite the removal of the stretchable endless belt for replacement purposes.

14. The ball pitching machine as defined in claim 1, including a split covering member suspended over the ball discharging mechanism and having an orifice in its front wall aligned with the path of the ball as it leaves the machine.

15. The ball pitching machine as defined in claim 1, including spacer washers engageable upon the bolts supporting the stretchably endless belts upon the secondary frame whereby stretchable endless belts of varying widths may be employed.

MARTIN GOLDMAN.
